The ornamental design for a movable electrical plug receptacle, as shown and described.

DESCRIPTION

FIG. 1 is a front and upper left perspective view of a movable electrical plug receptacle showing my new design with the receptacle removed from the support housing and in fragmented form for convenience of illustration;

FIG. 2 is a left end elevational view of a movable electrical plug receptacle showing my new design on a slightly reduced scale;

FIG. 3 is a right end elevational view thereof;

FIG. 4 is a rear elevational view thereof;

FIG. 5 is a front elevational view thereof;

FIG. 6 is a top plan view thereof; and,

FIG. 7 is a bottom plan view thereof.

FIG. 2
